APPARATUS FOR CLEANSING TUBULAR ELEMENTS

Ethan Allan Brown, Boston, and Norbert Benotti, Weston, Mass.; said Benotti assignor to said Brown

Application January 6, 1941, Serial No. 373,364

2 Claims. (Cl. 141—1)

The present invention relates to cleansing or sterilizing apparatus and particularly to apparatus for cleansing elongated tubular elements such for instance as pipettes. Pipettes, which are elongated tubes of relatively small diameter, usually fabricated of glass, are utilized in substantial numbers in hospitals and laboratories and other places where it is desired to measure accurately small volumes of liquid, and are usually required to be chemically clean when taken up for use. Cleaning pipettes has heretofore, in the usual case, been effected with the aid of chromic acid, each pipette being immersed in the acid and thereafter rinsed to remove any traces of acid which had not drained from the pipette upon its removal from the bath.

A primary purpose of the present invention is to provide an apparatus by means of which elongated elements such for instance as pipettes may be thoroughly and effectively cleansed and, if desired, rendered entirely sterile, the operations being not only effectively carried out but in a practically automatic manner so that but little time need be devoted to the task by the one whose duty it is to obtain the desired result. While the apparatus has been designed particularly for the purpose of chemically cleaning tubular elements such as pipettes, it will be appreciated by one skilled in the art that the apparatus is eminently suitable for rendering sterile elongated tubular elements of other types and objects of other shapes.

The complete apparatus contemplated by the present invention includes three principal elements, the first being a holder into which may be placed pipettes or tubes after they are soiled in use, the holder having capacity to receive a substantial number of the tubular elements, the other two pieces of apparatus comprising containers within which the holder may be successively placed, one of the containers being a simple tubular receptacle to receive and hold a body or bath of chromic acid, the second container, or the third and final piece of apparatus, being generally similar to the second but having means for intermittently flooding the same with fluid and emptying the fluid thus introduced, so that when the holder is placed within this second container the tubes or pipettes which it contains are automatically subjected to successive washings with a suitable washing fluid, generally water. When the holder containing soiled pipettes or the like is placed in the acid container, the acid will contact with all areas of each and will dissolve extraneous matter and

render such surface absolutely clean and sterile, the holder with its contents being allowed to remain in the bath of acid for a length of time quite sufficient to ensure destruction of any organic or inorganic material which may be located upon the pipette surfaces or upon the surfaces of the holder itself.

Where the apparatus is employed in a laboratory, it is customary to allow the pipettes and the holder in which they are supported to remain in the acid bath overnight. Thereafter the holder is removed from the first container and is placed in the second container which, as has previously been explained, is provided with means for automatically flooding it with rinsing liquid and thereafter emptying this body of liquid so that the pipettes or tubes which have previously been immersed in acid are subjected to repeated immersions in clean rinsing liquid in an entirely automatic manner. No attendant is required to concern himself with the operation of the apparatus during either the acid treatment step or the rinsing step and the entire cleansing operation is not only carried out in the most effective and efficient manner but with only the slightest amount of attention.

The invention may be embodied in apparatus the various elements of which vary in design and arrangement and one form of the invention which has been heretofore employed with eminent success in the cleansing of pipettes is illustrated by way of example in the accompanying drawing, in which:

Figure 1 shows the holder partially in section and partially in elevation, together with the first container, or the acid bath container, which is shown in axial section;

Figure 2 is a generally similar view but showing the holder positioned in the rinsing container;

Figure 3 is a section on line 3—3 of Figure 1; and

Figure 4 is a section on line 4—4 of Figure 2.

The holder is generally indicated by the numeral 10 in the drawing, the acid container by the numeral 11, and the rinsing liquid container by the numeral 12. The holder 10 is in the form of a tube the diameter of which is relatively small as compared with its length, which is open at its stop, and the bottom 10' of which is perforated for the passage of fluid, the tube being preferably a hollow cylinder of glass and its bottom 10' being an upwardly bulging and preferably conical member provided with a plurality of perforations 10² by means of which liquid can

pass into the interior of the holder or escape therefrom. At its apex or highest point the bottom 10' is provided with an opening and a tubular extension 10² the annular end surface of which is disposed in a plane inclined to the horizontal. It will also be observed that the conical bottom is projected outwardly beyond the outer surface of the cylindrical portion 10 of the tube and the annular edge or periphery of the conical bottom is adapted to engage any flat supporting surface, and to function as a standard or supporting base for the holder, which may be placed on a table, floor, or upon any flat surface to support the holder in an upright position to receive soiled tubes or pipettes.

Several pipettes are indicated by the numerals 13, 13 and it will be perceived that the end surfaces of each pipette are normal to its axis so that the lower end of the pipette will have point contact only with the upper surface of the conical bottom 10' of the holder, or with the inclined upper surface of the tubular extension 10². This makes certain that the opening in the bottom of each pipette will not be blocked or obstructed in such manner that the flow of liquid into or out of the interior of the pipette will be hindered. The holder, as will be observed, is somewhat longer than the container 11, also longer than the container 12 so that, when placed in either of these containers, its top portion will protrude. This is to provide the attendant with a convenient grasping portion, the upper end of the holder in reality comprising a handle by means of which the holder may be lifted, transported, and placed where desired. The diameter of the conical member 10' is, at its base, only slightly less than the diameter of the container 11. This ensures that the holder must be moved downwardly in the container 11 relatively slowly when it is first introduced, permitting the contained acid to flow into the interior of the holder through the apertures in the bottom, eliminating the possibility of displacing the acid bath so rapidly as to cause it to overflow from the container 11, and safeguarding these two elements of the apparatus against possible breakage due to rapid impact, both being of glass and therefore rather easily broken. This slow descent also allows the cleansing fluid to rise slowly in the pipettes, sweeping them upwards and so washing out the substances which soiled them.

When the holder is placed in the container 12, it occupies the same relative position in that container as it does in the container 11, as readily perceived from an inspection of Figure 2. Container 12 is provided with means for introducing a rinsing liquid, for instance water, into the same at the bottom and with means for automatically emptying the container after each flooding so that pipettes within the holder are repeatedly bathed with successive applications of clean rinsing liquid until all traces of the acid previously applied for cleaning purposes have been removed.

Thus, container 12 is provided at a point closely adjacent its bottom with an aperture to receive a cork or packing element 15 which element, which is preferably fabricated of rubber, is axially perforated to receive the horizontally extending tube or duct 16 the inner end of which, indicated at 16', is upwardly directed as shown and terminates in a discharge port or nozzle. It is through the duct 16 that the rinsing liquid is introduced into the container 12 and the rate of inflow of such liquid may be regulated, as by means of the control valve diagrammatically in-

dicated at 17. A syphon is generally indicated at S, this syphon having a portion of one leg within the container and the other leg wholly without the container, the upper ends of the two legs being connected by the curved portion 20. Thus the outer leg 21 of the syphon extends from the curved portion 20 to a point below the bottom of the container 12.

The inner leg is formed in three sections, a relatively short section 22 which is integral with the curved portion 20, an intermediate section 23, and a lower section 24. The lower section has its lower end terminating just above the bottom of container 12 and is provided with a horizontally disposed integral part 24' adjacent its upper end which passes through a central aperture formed in a cylindrical bushing or packing member 25 fabricated of rubber or the like and which tightly engages the cylindrical wall surface of an aperture formed in the side of the container. Part 24' is also integral with the upper terminal portion 24² of the lower leg section, which terminal portion is parallel to the outer leg 21. The intermediate section 23 is detachably connected to the upper and lower sections 22 and 24 by coupling members or sleeves 26 and 27, respectively, and by this arrangement vertical adjustment of the position of the curved upper portion 20 of the syphon may be readily effected. Thus, if it be desired that the curved portion 20 be lowered, section 23 of the inner leg of the syphon may be removed and replaced by a shorter section.

The diameter of the tube of which the syphon is formed is substantially greater than the diameter of the tube 16 through which rinsing liquid is introduced into the container and the syphon will, when it becomes active, and with the rate of fluid inflow relatively low, as is preferred, evacuate a body of liquid which may be within the container in much less time than was required to introduce the liquid. In the ordinary use of the rinsing mechanism water will be caused to flow into the bottom of the container in a constant stream and the level of the surface of this liquid will gradually rise, both within and without the holder 10, the water flowing into the interior of the holder through the apertures 10² in the bottom, and into the space between the concentric holder and container walls through the apertures 30 and 31 formed as notches or cutouts in the lower margin of the holder bottom 10'.

The rinsing fluid passing into the holder will, in part, pass upwardly between the several pipettes or other tubes which the holder contains and in part will pass upwardly through the elongated apertures formed in these tubular elements, each pipette or tube being washed or rinsed both interiorly and exteriorly. The inflow of rinsing liquid will continue uninterruptedly until the pipettes or tubes within the holder are completely immersed, for instance rising to the level indicated by the line A—A in Figure 2. When the liquid level rises to this point, however, the inner leg of the syphon is completely full and liquid begins to flow over into the outer leg 21 of the syphon, thus starting the syphon action, the syphon action continuing relatively rapidly until the container 12 is substantially emptied of its washing liquid.

When the lower end of the inner leg of the syphon is exposed, the syphon is broken and the outflow of wash liquid is discontinued, the inflow continuing, however, until the level of the surface of the liquid within the container 12 again gradually rises until it reaches the level indicated by

the line A—A. At this point the siphon action is again commenced and the container is again emptied. If desired, the lower portion 24 of the inner leg of the siphon may be provided, near the bottom thereof, with an aperture 32 to effect interruption of the siphon action at a point above the bottom to the tube, when the inflow of water through the tube or duct 16 is relatively rapid.

It will be observed that the two notches or cutouts 31 are relatively large and it is essential that such apertures be formed in the periphery of the bottom member 10' to receive the tubular section 24 of the siphon as the holder is introduced into and withdrawn from the container 12, the diametrically opposed notch or recess 31 receiving the water duct or conduit 16 when the holder is resting on the container bottom. The rinsing action may be allowed to continue indefinitely but, of course, to avoid wastage of water, the action is stopped after the pipettes have been thoroughly rinsed.

It will be seen that the apparatus comprises three essential major portions; the holder, which functions as a receptacle for pipettes; the container for the chromic or other cleaning fluid and the container for the rinsing fluid, with its associated means for effecting withdrawal of water which has been once used for rinsing and the prompt if not immediate replacement of the water removed with a fresh body of rinsing water. The several elements of the invention are of the utmost simplicity, are attractive in appearance, and quite inexpensive to fabricate and use. Obviously, minor changes may be made without departure from the invention.

Having thus described the invention, what is claimed as new and desired to be secured by Letters Patent is:

1. Apparatus for cleansing with liquid elongated tubular open ended elements, comprising,

in combination, a cylindrical vertically disposed container having an inlet conduit for cleaning liquid, said conduit entering through the side wall of the container adjacent to the bottom and extending inwardly along said bottom surface and opening at a centrally disposed point, an automatic intermittently actuated siphon outlet means for the container, a removable holder for introducing said elements into the container, said holder being substantially cylindrical and provided with a substantially conical upwardly bulged perforated bottom wall, said bottom wall extending downwardly to form flared lower marginal edges, said flared edges being notched to accommodate said inlet conduit.

2. Apparatus for cleansing with liquid elongated tubular open ended elements, comprising, in combination, a cylindrical vertically disposed container, an inlet conduit for cleaning liquid opening into said container, an inverted U-shaped tube providing an automatic intermittently actuated outlet siphon for the container, at least a portion of one leg of said tube being disposed interiorly of said container and close to the wall thereof, a removable holder for introducing said elements into the container, said holder being substantially cylindrical and provided with a perforated bottom wall and flared lower marginal edges, the walls of the holder being spaced from the walls of the container and the flared bottom edges of said holder being approximately the same diameter as the internal diameter of said container with sufficient clearance for ready removal, said flared edges being notched to provide for the passage thereof past the inner leg of the U-shaped siphon tube.
